UNITED STATES PATENT OFFICE.

JAMES HADDON DAVIDSON, OF WATERTOWN, MASSACHUSETTS, ASSIGNOR TO HOOD RUBBER COMPANY, OF WATERTOWN, MASSACHUSETTS, A CORPORATION OF MASSACHUSETTS.

GUM-STOCK DEFLECTOR FOR RUBBER CALENDERS.

Application filed May 7, 1927. Serial No. 189,694.

This invention relates to a gum stock deflector for rubber calenders, and has for its object to provide a device for deflecting plastic rubber stock from the ends of a calender roll toward the center thereof, thereby preventing said stock from accumulating upon the periphery of said roll and passing off the ends thereof and eventually entering the journals for said roll, or from collecting upon the frame supporting said roll.

In impregnating fabric with rubber in a calender machine, the rubber stock is transferred from a mass of the same to the periphery of a roll and the latter co-operates with another roll to force the stock into the fabric as the latter passes therebetween. It is evident that all of the stock may not be transferred from the first-mentioned roll to the fabric, and as the stock is sticky that a certain amount thereof will adhere to the first-mentioned roll when the impregnated fabric is disengaged therefrom, and unless this excess stock is removed from the end portions of the roll it will accumulate thereon to such an extent that it will eventually be squeezed off the ends of the roll, and not only gum up said ends, but also the journals for the roll and portions of the machine adjacent thereto.

The device of this invention keeps the periphery of the roll at the opposite ends thereof perfectly clean and prevents the excess stock from passing a predetermined point upon the periphery thereof.

The invention consists in an improved gum stock deflector for calender rolls as set forth in the following specification and particularly as pointed out in the claims thereof.

Referring to the drawings:—

Figure 1 represents a front elevation of an end portion of a calender roll, a gum stock deflector embodying my invention being illustrated associated therewith.

Fig. 2 is a side elevation of the deflector as viewed from the right of Fig. 1, a portion of a calender roll being illustrated in connection therewith.

Fig. 3 is a detail horizontal section taken on the line 3—3 of Fig. 1. Fig. 4 is a diagrammatic view showing a deflector at each end of a calender roll.

Like numerals refer to like parts throughout the several views of the drawings.

In the drawings, 5 represents a portion of

the side frame of a calender and 6 represents an end portion of a calender roll, the latter being rotatably mounted in a well-known manner upon the frame 5. Rigidly secured to the inner face of the frame 5 is a bracket 7 and rigidly secured in any suitable manner in said bracket, and projecting laterally therefrom, is a stud 8, the latter constituting a pivot under certain conditions for a deflector 9.

The deflector 9 embodies therein an arm 10 having a slot 11 formed therein, through which the stud 8 projects, and said deflector 9 is loosely mounted to slide upon said stud toward and away from the periphery of the calender roll 6. The deflector 9 is prevented from moving longitudinally upon the stud 8 by a collar 12, which is rigidly secured to said stud, said collar bearing against the face of the arm 10.

The deflector 9, which constitutes a segmental helical member and which is preferably constructed of a fairly soft composition metal, so that it will wear down in service and not destroy the surface of the calender roll, is forced against the periphery of the roll by a pair of adjusting screws 13, the latter being mounted in the bracket 7 with the extremities of said screws engaging the front edge of the deflector. Check nuts 14 are provided for the screws 13.

The working face of the deflector 9 is curved at 15, thereby forming a scraping edge 16 where the curved surface intersects a face 17 of the deflector, and said working face of said deflector is preferably disposed at such an angle to the periphery of the calender roll that as the latter is rotated in the direction of the arrows *a* and *b* in Figs. 1 and 2 respectively, that the material adhering to the periphery will be deflected inwardly along said periphery when it comes into engagement with the edge 16 and surface 15 of the deflector. The curved surface 15 furthermore is concave and contains the scraping edge 16, and, being approximately normal to the surface of the calender roll, acts to prevent the excess stock from piling up and accumulating upon the working surface of the deflector and tends to readily force the stock inwardly along the periphery of the roll until it passes from the deflector at the innermost face 18 thereof.

It will be understood that the calender roll

6 is equipped with two of the devices hereinbefore described, said devices being located at opposite ends of said roll and being constructed right and left hand, the scraping edges 16 and working faces of the deflectors converging toward each other in the direction of feed of the calender roll as illustrated diagrammatically in Fig. 4.

The general operation of the device hereinbefore described is as follows:—The calender roll 6 rotating continuously in the direction of the arrows *a* and *b* in Figs. 1 and 2 respectively and having a small amount of excess rubber stock adhering thereto after the fabric is disengaged therefrom is engaged by the deflector 9, the surface 17 of which is held closely in engagement with the periphery of said roll by the screws 13, and as said roll rotates, the edge 16 of the deflector scrapes the adhesive material from the periphery of said roll at the end thereof and the working face 15 acts to guide the excess material inwardly causing said material to pass from the innermost 25 point of the deflector at the surface 18 thereof, from which point the roll returns the material to the point where it was originally applied to the roll. The deflector 9 is held against the periphery of the roll 6 by 30 the adjusting screws 13, and as the surface 16 of the deflector becomes worn, the adjusting screws are manipulated to offset the wear. The inward movement of the deflector 9 toward the periphery of the roll 6 is 35 permitted by the presence of the slot 11 in the arm 10, and when the deflector 9 is not held closely against the periphery of the roll, the stud 8 acts as a pivot for said deflector.

I claim:

40 1. A gum stock deflector having, in combination, a calender roll, a bracket, a deflector pivotally and slidably mounted upon said bracket, and means upon said bracket to force said deflector against the periphery 45 of said roll.

2. A gum stock deflector having, in combination, a bracket, a segmental helical deflector pivotally and slidably mounted upon said bracket, and means to move said deflector upon the pivot thereof against the periphery of said roll, whereby material adhering to said roll may be deflected inwardly along the periphery thereof. 50

3. A gum stock deflector having, in combination, a calender roll, a bracket, a deflector mounted upon said bracket, and means to force said deflector against the periphery of said roll, said deflector being provided with an edge for scraping said roll and having a concave curved surface 60 approximately normal to the surface of the roll and containing said scraping edge. 55

4. A gum stock deflector having, in combination, a calender roll, a bracket, a deflector pivotally and slidably mounted upon said bracket, and means to force said deflector against the periphery of said roll, said deflector being provided with an edge for scraping said roll and having a concave curved surface approximately normal to the 70 surface of the roll and containing said scraping edge, said edge and surface being positioned relatively to said roll to deflect material adhering to said roll inwardly along the periphery thereof. 75

5. A gum stock deflector having, in combination, a calender roll, a bracket, a pivot mounted in said bracket, a segmental helical deflector slidably mounted upon said pivot, and means to force said deflector against the 80 periphery of said roll, said deflector being provided with an edge for scraping said roll and having a curved surface containing said scraping edge, said edge and surface being positioned relatively to said roll to deflect 85 material adhering to said roll inwardly along the periphery thereof.

In testimony whereof I have hereunto set my hand.

JAMES HADDON DAVIDSON.
